UNITED STATES PATENT OFFICE.

LOUIS N. D. WILLIAMS, OF OGONTZ, PENNSYLVANIA, ASSIGNOR TO SCOTT & WILLIAMS, INCORPORATED, OF OGONTZ, PENNSYLVANIA, A CORPORATION OF NEW JERSEY.

RIB-KNITTING MACHINE.

1,137,561.

Specification of Letters Patent. Patented Apr. 27, 1915.

Application filed June 28, 1911. Serial No. 635,882.

To all whom it may concern:

Be it known that I, LOUIS N. D. WILLIAMS, a citizen of the United States, residing in Ogontz, Montgomery county, Pennsylvania, 5 have invented certain Improvements in Rib-Knitting Machines, of which the following is a specification.

The object of my invention is to so construct a machine for knitting ribbed fabrics 10 of the character shown in R. W. Scott's Patent 928,222, dated July 13, 1909, that said fabrics can be knitted in fine gages without the risk of latch interference, the devices employed being to this extent an improvement 15 on the machine patented to said R. W. Scott on the 8th day of March, 1910, Number 951,706.

In the accompanying drawings—Figure 1 is an inverted plan view of part of the dial cam cap of the machine, showing two sets of cams and also showing the undersides of two of the yarn feeding devices; Fig. 2 is a view showing, in a flat plane, one of the sections of the ring which carries the cams for 25 operating the cylinder and showing also the inner side of one of the yarn feeds; Fig. 3 is a similar view of another section of said cam ring, and showing also the inner side of the other yarn feed; Fig. 4 is a sectional view 30 of part of the cam cylinder and dial of the machine with a cylinder and dial needle illustrating the latch interference which my invention is intended to prevent; Fig. 5 illustrates the cylinder and dial needles in the 35 relation to each other shown in Fig. 4, and Figs. 6 to 15, inclusive, are views showing parts of the cylinder and dial and cylinder and dial needles in the relations which they assume to each other at different times in 40 the operation of the machine.

As will be understood on reference to the 45 patents before referred to the fabric in question is formed by placing in the cam carriers, cams of such formation that they will have an alternating primary and secondary 50 action upon the needles.

In knitting fine gage fabric with the arrangement of cams shown in Patent 951,706, 55 latch contact is liable to take place, as shown in Figs. 4 and 5, because of the retraction of the primary needle while the secondary needle is still projected.

In knitting machines there is always more or less lateral displacement of the spoon of 60 the latch when the same is closing, such dis-

placement being due to the sidewise movement of the needles under the thrust of the cams upon the butts, to the play of the needles in their grooves, and to the play of the latch in its slot, and, in fine gage machines of the type to which I have referred, this lateral displacement is frequently such that the closing latch of the retracting primary needle will strike the back of the still projected secondary needle with resultant 65 injury to or breakage of the latch, which renders its needle incapable of performing its proper function in the further operation of the machine.

My present invention consists in so operating 70 the primary and secondary needles that the liability of latch interference will be overcome.

On reference to Figs. 1, 2 and 3, it will be noted that the cam 1 of the dial cam cap is 75 a primary cam, the cam 3 of said dial cam cap is a secondary cam, the cam 2 of the cylinder cam ring is a secondary cam and the cam 4 of said cylinder cam ring is a primary cam, and these parts are located in the 80 machine with reference to each other as indicated by the lines *a*, *b*, *c*, *d*, *e*, *f*, *g*, *a'*, *b'*, *c'*, *d'*, *e'*, *f'*, *g'*, so that the primary cam 1 of the dial cam cap acts in conjunction with the secondary cam 2 of the cylinder cam ring 85 and the primary cam 4 of said cylinder cam ring acts in conjunction with the secondary cam 3 of the dial cam cap.

When the needles are at station *a*, the hook of the dial needle is slightly outside 90 of the edge of the dial and the hook of the cylinder needle is slightly beyond the upper edge of the cylinder, as shown in Fig. 6. At station *b* the dial needle has been projected sufficiently to cause the stitch thereon 95 to open the latch, as shown in Fig. 7, and has then been retracted, as shown in Fig. 8, and held in the retracted position until station *c* is reached, at which point the cylinder needle has been projected so as to cause the stitch 100 upon it to open its latch, as shown in Fig. 8, projection of each needle so as to open its latch being effected while the other needle was retracted so that there can be no liability of latch interference at this stage of 105 the operation.

At station *d* the dial needles have been fully projected, as shown in Fig. 9, the cylinder needles retaining the same position as at station *c*. At this point the yarn is fed 110

to the dial needles by the yarn guide x which carries a latch closer x' , whereby, as the dial needle is retracted, its latch will be closed by said member x' of the yarn guide 5 before it reaches the cylinder needle.

At station e the dial needle has been fully retracted so as to cast off its stitch and draw a new loop, but before said retraction of the dial needle is completed, the cylinder needle 10 has been lowered slightly, as shown in Fig. 10, by the depression in the cylinder cam, between the stations d and e , and the yarn between the dial loops is laid over the open latches of the intervening cylinder needles.

At station f the cylinder needle has been 15 fully retracted so as to cast its stitch and draw a new loop, the closing of the latch not being interfered with, as the dial needle is still retracted, having only been eased up 20 slightly, as shown in Fig. 11, so as to again assume the starting position shown in Fig. 6, and at station g the cylinder needle has also 25 been slackened up slightly so that both needles are now again in the position shown in Fig. 6.

At stations a' and b' the needles bear the same relation to each other as at stations a and b represented in Figs. 6 and 7, but at 30 station c' the cylinder needles have been projected to the full extent, as shown in Fig. 12, the dial needles still remaining in the retracted position to which they have been moved after having been projected, as shown in Fig. 7, so as to open their latches.

At station d' the dial needles have also 35 been fully projected, as shown in Fig. 13, and the yarn guide y is feeding the yarn to the needles, said yarn guide having a latch closer y' which engages with the latches of the cylinder needles and closes 40 the same when said needles are being retracted in passing from the station d' to the station e' , the dial needles at the same time being slightly retracted, so that the yarn be-

tween the new loops drawn by the cylinder 45 needles will be laid over the latches of the dial needles, the parts when they reach the station e' being in the position shown in Fig. 14.

While the dial needle is being fully re- 50 tracted in passing from station e' to station f' the cylinder needle will be slightly projected so as to slack up the stitch upon it, as shown in Fig. 15, and will be retained in that position while the dial needle is being 55 similarly slackened up in passing from station f' to station g' , the parts being now again in the position shown in Fig. 6, preparatory to a repetition of the operations described.

At no stage in the operation of my im- 60 proved machine is there any chance for interference either of an opening or closing latch of one needle by contact with an ad-joining needle, consequently the difficulties heretofore experienced in the operation of 65 machines of the type to which my invention relates are effectually overcome.

I claim:

The combination, in a knitting machine, 70 of needle carriers having needles so disposed that the planes of movement of the needles cross each other, with a latch closer for one set of said needles, means for advancing said set of needles to such extent that said latch closer can operate in front of the other set 75 of needles, and cams for operating the latter set of needles so that they will first clear their stitches and then be withdrawn sufficiently to receive the yarn on their latches as the stitches are drawn by the first set 80 of needles.

In testimony whereof, I have signed my name to this specification, in the presence of two subscribing witnesses.

LOUIS N. D. WILLIAMS.

Witnesses:

LEONA G. WHINNA,
FANNY LEECH.

It is hereby certified that the residence of the assignee in Letters Patent No. 1,137,561, granted April 27, 1915, upon the application of Louis N. D. Williams, of Ogontz, Pennsylvania, for an improvement in "Rib-Knitting Machines," was erroneously given as "Ogontz, Pennsylvania," whereas said residence should have been given as *Camden, New Jersey*, as shown by the records of assignments in this office; and that the said Letters Patent should be read with this correction therein that the same may conform to the record of the case in the Patent Office.

Signed and sealed this 11th day of May, A. D., 1915.

[SEAL.]

R. F. WHITEHEAD,
Acting Commissioner of Patents.
